UNITED STATES PATENT OFFICE.

CARL BARTELS, OF HAMILTON, OHIO, ASSIGNOR TO THE MOSLER SAFE COMPANY, OF HAMILTON, OHIO.

SAFE OR VAULT.

971,344.

Specification of Letters Patent. Patented Sept. 27, 1910.

Application filed April 29, 1910. Serial No. 558,444.

To all whom it may concern:

Be it known that I, CARL BARTELS, a citizen of the United States, residing at Hamilton, Butler county, Ohio, have invented 5 certain new and useful Improvements in Safes or Vaults, of which the following is a specification.

This invention pertains to safes or vaults of round door type, and relates to improvements for causing the door to move squarely 10 into and out of its seat, and to prevent the rotating of the door into improper angular position while it is out of the door-jamb, and to facilitate the adjustment of door-carrying 15 mechanism to doors of uncuttable manganese steel.

My improvements will be readily understood from the following description taken 20 in connection with the accompanying drawings in which:

Figure 1 is a front elevation of a safe exemplifying my present improvements; Fig. 2 a front elevation of the door and crane-hinge, the door-bearing appearing in 25 vertical section in the plane of line *a* of Fig. 3: Fig. 3 a horizontal section of the safe-front, door &c., in the plane of line *b* of Figs. 1 and 2: Fig. 4 a plan, mainly diagrammatic, of the hinge mechanism, the gear-disk having 30 a portion appearing in horizontal section in the plane of line *c* of Fig. 2: and Fig. 5 a horizontal section through door-parts, in the plane of line *d* of Figs. 2 and 3.

In the drawings:—1, indicates the safe- 35 body, which may be assumed as an integral casting of manganese steel: 2, the tapering circular door-jamb in the front wall thereof: 3, the tapering circular door fitting the door-jamb and assumed as being a single 40 casting of manganese steel: 4, interrupted locking lugs on the periphery of the door, engaging behind similar lugs in the door-jamb: 5, the hinge-pivot: 6, the crane: 7, the door-bearing, in the form of a disk-like 45 casing having in its central portion a large bearing with its axis coinciding with the axis of the door: 8, pintles uniting the door-bearing with the free extremity of the crane, the common axis of these pintles being 50 parallel with the axis of the hinge-pivot on which the crane swings: 9, the gear-disk secured to the front of the door and having projecting outwardly from it a collared journal fitting the door-bearing: and 10, the 55 pinion carried by the door-bearing and en-

gaging teeth in the periphery of the gear-disk to serve in rotating the door.

All of the parts thus far referred to may be of well known construction and subject to the usual variations in the form of those 60 parts in safes of the character under discussion.

In safes of this character, with the doors held in the jambs by means of interlocking lugs of interrupted thread or interrupted 65 lug form, when the door has been rotated to bring the door-lugs out from behind the jamb-lugs, the door may be moved outwardly and withdrawn from the jamb and swung to entirely open position. But, owing to the 70 pivotal character of the crane-hinge, the door will naturally move out in the arc of a circle, instead of squarely, and the door is at liberty to rock on the pintles uniting it with the crane. The result is that, except 75

with very cautious manipulation, the door, as it moves out, is apt to shift sidewise and strike the sides of the jamb, thus interfering with general smoothness of operations in opening the safe. The natural desire would 80 be to have the door move smoothly outward free of contact with any jamb-parts the instant the outward motion started. The feature of my invention designed to take care of this matter will now be described. 85

Proceeding with the drawings:—11, indicates a plate of machineable metal firmly secured against the outer face of the door, between the door and gear-disk 9: 12, screws securing the gear-disk to plate 11: 13, rivets 90 cast integrally upon the outer face of the door and projecting through apertures in plate 11 and riveted upon the outside of the plate, it being understood that manganese steel, while uncuttable, is capable of being upset and riveted: 14, a pintle at the base of the door-bearing forward of and with its axis parallel with the axis of crane pintles 8: 15, a fixed cam rigidly supported by the safe-body at the base of the crane-hinge, the 100 surface of the cam starting at a given distance from the axis of hinge-pivot 5 and then curving outward and then becoming concentric with the hinge-pivot: 15' a horn around a portion of the cam and parallel 105 with it, giving the cam a grooved form: 16, a corrector-bar having one end pivoted to pintle 14, Fig. 4 showing a portion of this corrector-bar by a mere diagrammatic line: 17, the tail-end of the corrector-bar, the same 110

sliding through the rotary hinge-pivot 5, in other words, the corrector-bar connects the door-bearing with the main hinge, but is capable of endwise motion relative to the hinge: and 18, a pin projecting from the corrector-bar into contact with the cam in such manner that as the corrector-bar swings on the axis of the hinge-pivot it will be moved endwise relative to that pivot.

10 Taking the parts as they appear in Fig. 3, or appear diagrammatically in Fig. 4, the door is home in the jamb. Assume it to be turned to release the door-lugs from the jamb-lugs so that it is free to be withdrawn from the jamb. The opening motion of crane-pintle 8 will necessarily be the arc of a circle struck from the axis of hinge-pivot 5, and so also would be the path of outward movement of pintle 14 if the corrector-bar 20 were simply pivoted to the hinge-pivot. But as pintle 8 swings outwardly in its arc, the cam, acting on pin 18, forces pintle 14 to the left, the result being that the door, instead of maintaining its normal relationship to a line 25 cutting pintle 8 and hinge-pivot 5, has its inner portion moved somewhat to the right, or, more properly stated, it is prevented from moving to the left as it would naturally do. The result is that, notwithstanding the areal 30 motion enforced by the crane the erratic motions of the inner portion of the door are corrected for and the door caused to move squarely outward and inward. The curvature of the cam is such as to maintain the 35 proper correction of door motion until the door is so far out of the jamb that no further trouble can occur. When pin 18 shall have passed the extremity of horn 15' then the door may swing, in one direction, on 40 crane-pintles 8 to permit the open door to be put in some particular desired position. In other words, the cam is positive in controlling the door during a portion of the opening motion, giving freedom later.

45 Looking at Fig. 4, and assuming a line cutting the axes of pintles 8 and 14, that line may be viewed as a lever on the outer end of which corrector-bar 16 acts to pry the inner portion of the door to the right, or rather 50 keep it from going to the left, as the door swings open. The corrector-bar is shown as being mounted at the base of the hinged structure, but the correcting effect would be the same if it were mounted at the top of the 55 door, or at the top and the bottom, or at any place between the top and the bottom.

In opening a round door safe, the door is first rotated to free the door lugs from the jamb lugs, the free position being indicated by some sort of a stop, in the present instance by the end of the toothed segment on the gear-disk being reached by the pinion. The door may now be pulled open, the door-lugs passing through the gaps in the 60 jamb-lugs. If, when the door is but par-

tially withdrawn, the door be accidentally turned, lugs may again engage and interfere with the opening operation. I provide against this. Again, when the door is open, if it gets accidentally rotated it will not enter properly into the jamb when it is desired to close it. I provide that the door can be turned only when it is home in the jamb.

Proceeding with the drawings:—19, indicates a notch in the periphery of the gear-disk: and 20, indicates a projection carried by the crane and lying just outside the outer face of the gear-disk and in such position that when the door is rotated to bring the door-lugs into line with the gaps in the 70 jamb-lugs, notch 19 will be opposite projection 20.

When the door is home in the jamb and turned to lug-engaging position, the notch and projection will be as seen in Fig. 2. 75 Rotating the door, non-clockwise, brings the lugs to released position, and brings notch 19 in line with projection 20. Now, as the door begins to move outwardly, its corrected motion, as brought about by the cam, 80 causes the righthand portion of the door to approach the crane, the result being that projection 20 quickly enters notch 19. This occurs early in the opening motion and before the rear door-lugs have passed to the 85 front of the rear jamb-lugs, and after that the door cannot be rotated to cause lugs to engage while the door is being opened. When the door is again closed and clear 90 home in the jamb, the notch disengages 100 from the projection and the door may be properly turned to bring about the proper engagement of lugs. In the example illustrated the notch is shown as being in the gear-disk, and the projection as being carried by the base of the crane, the projection 105 on the crane entering the notch in the gear-disk. The same effect would flow from a projection on the gear-disk or any other outside portion of the rotary door to engage a 110 notch carried by the crane. In the construction illustrated the cam compels the door to approach parallelism with the crane as the door starts from its seat, and the projection and notch which lock the door against rotation after the door has started out from its 115 jamb are brought into action automatically as the door starts out. In the absence of the correcting device the projection and notch can be availed of, not automatically, of 120 course, but in a manner facilitating the opening and closing of the door. By practice one may swing the inner portion of the door to the right in pulling it open, thus putting the notch and projection into action, 125 and when the door is swung back clear open the notch and projection prevent the accidental turning of the door and keep it in condition for proper entry in the jamb when the door is to be again closed.

I claim:—

1. A safe comprising, a safe-body, a door thereto, a hinge-pivot supported by the safe-body, a crane hinged to the hinge-pivot, 5 pintles connecting the crane to the door, and a positive connection between the door and safe-body independent of the crane to cause the door to automatically approach parallelism with the crane as the door starts outwardly from its jamb, combined substantially as set forth.

2. A safe comprising, a safe-body, a door thereto, a hinge-pivot supported by the safe-body, a crane hinged to the hinge-pivot, 15 pintles connecting the crane to the door, a cam supported by the safe-body at the hinge-pivot, and a connection from the cam to the door independent of the crane to cause the door to automatically approach parallelism 20 with the crane as the door moves outwardly from its jamb, combined substantially as set forth.

3. A safe comprising, a safe-body, a door thereto, a hinge-pivot supported by the safe-body, a crane hinged to the hinge-pivot, 25 crane-pintles connecting the crane to the door, a cam supported by the safe-body at the hinge-pivot, a pintle carried by the door in front of the crane-pintles, and a corrector-bar pivoted to the front pintle and having its outer end controlled by the cam so as to cause the door to approach parallelism with the crane as the door moves outwardly from its jamb, combined substantially as set forth.

4. A safe comprising, a safe-body, a door thereto, a hinge-pivot supported by the safe-body, a crane hinged to the hinge-pivot, 40 pintles connecting the crane to the door, a grooved cam carried by the safe-body at the hinge-pivot, a pintle on the door in front of the axis of the pintles uniting the door and crane, a corrector-bar pivoted to said front pintle and supported at the hinge-pivot, 45 and a pin carried by the corrector-bar and engaging the groove of the cam, combined substantially as set forth.

5. A safe comprising, a safe-body, a door thereto, a hinge-pivot supported by the safe-body, a crane hinged to the hinge-pivot, 50 pintles connecting the crane to the door, a cam supported by the safe-body at the hinge-pivot, a pintle carried by the door in front of the pintles uniting the door and frame, a corrector-bar having one end pivoted to said front pintle and having its

outer end provided with a tail-piece sliding in the hinge-pivot, and a projection from the corrector-bar in engagement with the cam, combined substantially as set forth. 60

6. A safe comprising, a safe-body, a door thereto, a hinge-pivot supported by the safe-body, a crane hinged to the hinge-pivot, crane-pintles connecting the crane to the door, a cam supported by the safe-body at 65 the hinge-pivot, a pintle carried by the door in front of the axis of the crane-pintles uniting the door and hinge, a corrector-bar having one end pivoted to said front pintle and having its outer end supported at the hinge-pivot, a projection from the corrector-bar in engagement with the cam, and a horn carried by the cam exterior to said projection and serving to prevent the projection moving away from the cam until the end of the 70 horn is reached, combined substantially as set forth.

7. A safe comprising, a safe-body provided with a round door-jamb, a round door fitting therein, a door-bearing having the 80 door concentrically journaled therein, means for turning the door in the door-bearing, a hinge-pivot supported by the safe-body, a crane hinged to the hinge-pivot, pintles connecting the crane to the door, a connection 85 independent of the crane between the door and safe-body to cause the door to approach parallelism with the crane as the door starts outwardly from its jamb, and a coöperating recess and projection carried one by the door 90 and the other by the crane and adapted to interlock and prevent the rotation of the door when the door has been turned to unlocking angular position and while it is moving out of the jamb, combined substantially as set forth. 95

8. A safe comprising, a door formed of un-machineable metal and having studs formed integrally with it and projecting from its front face, a plate of machineable metal provided with apertures engaging the studs and held to the door by the riveting of the outer ends of the studs at the front face of the plate, a door-part disposed against the outer face of said plate, and screws uniting said 100 door-part to said plate, combined substantially as set forth. 105
